(57) **CLAIM**

I claim the ornamental design for electronic cigarette with cartridge, as shown and described.

DESCRIPTION

FIG. 1 is a right side, top perspective view of electronic cigarette with cartridge embodying my design;

FIG. 2 is a front plan view thereof, the rear plan view being a mirror image thereof;

FIG. 3 is a left side view thereof, the right side view being a mirror image thereof;

FIG. 4 is a top side view thereof; and,

FIG. 5 is a bottom side view thereof.

1 Claim, 5 Drawing Sheets

FIG.1

FIG. 2

FIG. 3

FIG. 4

FIG. 5
